UNITED STATES PATENT OFFICE.

CHARLES C. SCHUTTE, OF INDIANAPOLIS, INDIANA.

PNEUMATIC PAPER CONTROL FOR PRINTING PRESSES.

Application filed February 28, 1921. Serial No. 448,419.

To all whom it may concern:

Be it known that I, CHARLES C. SCHUTTE, a citizen of the United States, residing at Indianapolis, in the county of Marion and State of Indiana, have invented certain new and useful Improvements in Pneumatic Paper Control for Printing Presses, of which the following is a specification.

This invention relates to certain improvements for controlling the movement and for preventing the rolling up or other disarrangement of printed sheets of paper as they are discharged from the impression roller to the receiving table in that type of printing presses embodying reciprocating bed plates.

It is well known among workmen operating the above type of presses that after the latter have been operated at a high speed for a time the machines and also the paper passing therethrough become so charged with static electricity that the printed sheets of paper are handled with much difficulty, the paper seemingly having an affinity to stick to the carrying tapes, fly sticks and such parts of the printing press with which it may come into contact, so that the marring of the printed wet sheets presents a difficult problem. The effect of the static electricity is partially overcome at the present time by providing the printing press with a device for subjecting the surface of the printed paper, discharged from the impression roller, to the influence of heat, usually a gas flame. The same results may also be attained by reducing the speed of the press, or completely stopping the press at intervals. In the latter cases however, a considerable reduction or a complete suspension of the output of the press results. The devices heretofore in use have apparently reduced the amount of static electricity in the paper without materially affecting any reduction in the press structure itself, so that when the rapidly rocking fly sticks deposit a printed sheet on the receiving table of the press the tangs of the fly sticks are sufficiently energized and contain sufficient attraction to cause the corners of the deposited sheet of printed paper to be elevated and in many cases roll over upon the surface of the sheet when the fly sticks recede, so that the next printed sheet will be deposited upon the rolled over corners and in effect cause creases in the printed sheet below. These creased sheets of printed paper are classed as defectives and con-

stitute a considerable waste when turning out a high class job of printing on expensive paper.

The object of the present invention is not only to overcome the above mentioned difficulties, but a further difficulty—that of preventing the green printed surfaces of the sheets from being deposited flatly or "slapped" against the previously deposited printed sheet below, and thus prevent blurring.

Other characteristic features and objects of the generic invention will be made apparent to those skilled in the art, by the examination of the illustrative example of my improved type of organization which is depicted in the accompanying drawings and hereinafter more fully described. It will be understood however that the form of construction herein disclosed is to be considered only as one typical form of my organization, and is not to be regarded as limiting the mechanical scope of that organization.

In the drawings, which constitute an essential part of the present specification, Figure 1 is a fragmentary detail view in side elevation of a conventional style of printing press embodying a reciprocating bed-plate, showing the relative location of my invention thereto. Fig. 2 is a fragmentary detail view in side elevation of the opposite side of the press from that shown in Fig. 1, showing the location of my invention on that side of the press. Fig. 3 is a fragmentary detail plan view of a portion of the printing press, on the plane 3—3 in Fig. 2. Fig. 4 is a transverse sectional view of the receiving table, with one of the jogger-boards carrying a part of my invention shown in elevation, on the line 4—4 in Fig. 3, and in which the fly sticks are omitted. Fig. 5 is a fragmentary detail sectional view, on the line 5—5 in Fig. 4. Fig. 6 is a fragmentary detail sectional view on the line 6—6 in Fig. 3. Fig. 7 is a central vertical sectional view through one of the air regulating valves.

Referring to the drawings, 10 represents the main side frame members of the press; 11 the revoluble impression roller, and 12 the receiving table upon which the printed sheets of paper are deposited with the printed surface down. 13 are the usual belts or tapes, as they are known in the art, upon which the printed sheets are discharged and carried away from the impression roller. 110

14 are the usual fly sticks which move through an arc described by the curved arrow in Fig. 2 through the medium of a common rock-shaft 15 which is supported in the 5 side members 10 of the frame. These fly sticks, or tangs, 14, when disposed toward the impression roller 11 lie between and slightly below the upper surface of the tapes 13 so as to unobstruct the free movement of 10 the oncoming sheets of paper 16 conveyed from the impression roller 11. When a printed sheet of paper 16 is squarely over the fly sticks 14 the rock-shaft 15 is rocked through the medium of a cam 17, lever 18, 15 rack bar 19 and the mutilated pinion 20 to cause the fly sticks 14 to move from the dotted position to the full line position shown in Fig. 2, at which last mentioned position the fly sticks discharge and slap the 20 wet printed side of the sheet of paper broadcast upon the stack of the printed sheets 16 below. This method of discharging the wet side of a freshly printed surface of a slowly 25 drying sheet of high grade hard finished paper against the stack of sheets 16 below results in considerable loss through the blurring of the printed surfaces of the sheets unless an operator is especially employed at the receiving table for the purpose of interlaying each printed sheet with a sheet of 30 porous absorbent paper. This method however so increases the cost of production as to restrict its use.

Subjecting the printed sheets of paper discharged from the impression roller 11 to a 35 gas flame, which is old in the art, and to which attention has heretofore been directed, is accomplished by means of a pipe 22 which extends transversely of the press and 40 slightly in advance of the point where the printed sheet leaves the periphery of the impression roller 11 and discharges upon the guide fingers 23, best shown in Fig. 6. Pipe 22, which acts as a conductor for the gas 45 from a suitable source of supply, is provided in its lower surface with a series of fine perforations 24 through which the gas discharges against the adjacent surface of the moving paper.

50 Arranged immediately above and extending parallel with pipe 22 is a pipe 25 which conducts the air transversely of the press, and the latter pipe communicates with a conductor pipe 26 which extends to and communicates with casing 27 of a blast fan, whereby a constant flow of air is delivered to pipe 25. Pipe 25 is provided in its lower edge with a series of perforations through 55 which the air is discharged upon the adjacent surface of pipe 22, so that the latter pipe acts as a deflector for disseminating and effecting a better distribution of the air across the printed surface of the sheet during its movement along the tapes 13, than 60 would otherwise obtain. Consequently, this

distribution of the discharged air promotes several beneficial results; first, it causes a corresponding increase in the range of diffusion and effective distribution of the heat from the gas flame across the surface of the 70 printed sheet; second, reducing the length of time required in drying the printing ink, and, third, the moving current of air preventing the turning or rolling up of the edges of the swiftly moving printed sheets 75 of paper along the tapes 13.

As heretofore mentioned, the tapes 13 receive in successive order each printed sheet of paper from the impression roller 11 and convey it directly over the fly sticks 14, the 80 fly sticks then removing the sheet of paper from the tapes and conveying and depositing it with the printed side down upon the stack 16 of the printed sheet resting upon the table 12 of the press. The fly sticks 14 85 undergo a rapid rocking movement which is synchronized with the movement of impression roller 11 to permit the fly sticks to deposit a printed sheet upon table 12 and thence return to their initial position in 90 order to receive the next printed sheet discharged from impression roller 11. This rapid movement of the fly sticks 14 results in slapping the broad freshly printed surface of the sheet of paper harshly and with 95 sufficient force against the adjacent surface of the stack of printed sheets 16 on table 12 to cause considerable blurring or smearing of the ink which results in a corresponding amount of waste. To overcome this objection is one of the chief objects of the present invention, and is accomplished by means of certain construction and arrangement of parts which will now be described.

Table 12 is provided with the usual jogger-boards 30 by which the edges of the irregularly deposited printed sheets of paper are maintained in a symmetrically disposed stack 16, and as the area of the sheets of paper for different jobs varies the jogger-boards 30 must from time to time be adjusted relatively to each other to suit the conditions. Hence, in order that the present invention may be advantageously employed for effecting my improved landing of the 115 printed sheets of paper upon table 12 as the same are discharged by the fly sticks 14, I employ one of the jogger-boards 30 for the mounting of my invention and for maintaining its effective operative position 110 throughout the varying degrees of adjustments of said jogger-boards. The construction and arrangement of the foregoing parts comprise essentially a pair of parallel conductor pipes 35 and 36 for conveying and 120 discharging air at determined points and at predetermined times for the purposes, first, of controlling the movement of the printed sheets of paper between the time they leave the fly sticks 14 and land upon table 12, and, 125 130

second, for maintaining the sheets in a flat position upon table 12, by preventing the corners and edges of the sheets from curling up. The first of these objects is attained by 5 means of the conductor pipe 35 which is preferably arranged to extend parallel along the rear surface and is attached to the back side of one of the jogger-boards 30 by means of the air discharge nozzle cups 37 through 10 which the discharge of the air is effected. I usually employ two of the cups 37 one of which is located near each end of the jogger-board 30, but more cups can be employed if desired. Each cup 37 communicates with an 15 aperture 38 which extends transversely through jogger-board 30 so that the air from pipe 35 is discharged in a horizontal stream across table 12 for promoting the conditions desired as the printed sheets are 20 deposited upon table 12.

Pipe 35 communicates at one side of the press frame with a flexible branch pipe 40, and this pipe communicates with a main feed pipe 41 which extends to and communicates 25 with an air compressor consisting of a cylinder 42 and a piston 43 which operate within said cylinder. Piston 43 is connected to and operated by a crank arm 44 which is mounted on the same shaft 45 upon which 30 cam 17 is mounted and through which a rocking movement is imparted to the fly sticks 14, so that shaft 45 provides the medium for so synchronizing the movements of the fly sticks 14 and the piston 43 to 35 cause air to be discharged through apertures 38 and cross table 12 during the time that the fly sticks are depositing a printed sheet upon the table 12. As a printed sheet of paper leaves the fly sticks 14 its speed of 40 travel is gradually arrested by reason of the contact of its broad surface with the horizontal current of air discharging from apertures 38. Instead of the sheet of printed paper being thrown or slapped harshly upon 45 the stack 16 it settles downwardly unevenly, the time required for reaching a position of rest depending upon the rapidity with which the air is displaced from beneath the sheet, as induced by the weight of the sheet. 50 The time for the sheet of paper to reach a position of rest being considerably extended over that heretofore consumed, it necessarily follows that the time of exposing the printed surface of the sheet of paper to the air currents is correspondingly increased, and thereby correspondingly decreasing the length of time required for drying the ink. Pipe 40 is also provided with a check valve 55 (Fig. 7) by which the air may be controlled to effect a discharge through apertures 38 when the fly sticks 14 have reached a predetermined position relatively to the point where the printed sheets of paper are discharged. Valve 50 is seated by a spring 60 65 51 the tension of which may be increased

or decreased by means of a thumb-screw 52 so as to effect a discharge of the air when the air in cylinder 42 reaches a predetermined pressure.

The second object as above set forth is of 70 equal importance—that of maintaining the sheets of paper in a perfectly flat position upon table 12 and thereby prevent creases being formed in the sheets which result from the curling up of their corners and edges. 75

This object is attained by means of conductor pipe 36, heretofore referred to, which extends slightly above and parallel with and secured to the upper edge of jogger-board 30, as best shown in Figs. 2 and 5. 80 Pipe 36 communicates with a pipe 41' which in effect is a continuation of the main supply pipe 41 which leads to the compressor 42. Pipe 36 is provided with a plurality of air discharge apertures 55 in its lower surface so as to cause the air to be discharged 85

downwardly upon the adjacent edges and corners of the printed sheets of paper resting upon table 12. All of the apertures 55 in pipe 36 are usually closed by means of the screw plugs 56 with the exception of the ones through which it is desired to effect the discharge of the air, as best shown in Fig. 4. As the printed sheets of paper may vary in size the points of discharge of the air may also be varied along pipe 36 by closing the apertures 55 which are open and opening some of the apertures which are closed. It is not essential that the centrally located apertures 55 remain open 95 when the printed sheets are not slit through the center, but where the sheets of paper are slit in the middle when leaving the impression roller 11, along the dotted line A in Fig. 3, it is desirable to employ a blast of air for holding the adjacent corners of the divided sheets flat upon table 12. Pipe 41' is also provided with a check valve 60, similar to valve 50, and this valve is adjusted so that a discharge of air through apertures 55 in pipe 36 will be delayed until the moment the fly sticks 14 start to recede, at which time the blast of air prevents the sheet of paper from adhering to the fly sticks 14 and also serves to hold the edges 100 and corners of the sheet flat against the table 12 or the sheets of paper previously deposited upon said table.

Having thus fully described my said invention, what I desire to secure by Letters 120 Patent, is—

1. In a printing press, the combination with an impression cylinder, and a reciprocating type-bed, of a gas conductor pipe extending parallel with the impression cylinder and transversely of the path of travel of the sheets of printed paper, for subjecting the latter to a gas flame, an air conductor pipe extending parallel and slightly above the gas pipe and provided with a 125 130

series of downwardly disposed air discharge openings for discharging air across the heat waves generated by the gas flame for effecting an increased range and distribution 5 of the heat across the surface of the printed sheets of paper.

2. In a printing press, the combination with an impression cylinder, and a reciprocating type-bed, of a gas conductor pipe extending parallel with the impression cylinder and transversely of the path of travel 10 of the sheets of printed paper, for subjecting the latter to a gas flame, an air conductor pipe extending parallel and slightly above

the gas pipe and provided with a series 15 of downwardly disposed air discharge openings for discharging air across the heat waves generated by the gas flame for effecting an increased range and distribution of the heat across the surface of the printed 20 sheets of paper, and means for delivering an adequate supply of air to said conductor pipe.

In witness whereof, I have hereunto set my hand and seal at Indianapolis, Indiana, 25 this 23rd day of February, A. D. one thousand nine hundred and twenty-one.

CHARLES C. SCHUTTE. [L.S.]
